UNITED STATES PATENT OFFICE.

CHARLIE S. RIGGIN, OF KANKAKEE, ILLINOIS, ASSIGNOR TO THE JAMES H. WATSON COMPANY, INC., OF BRADLEY, ILLINOIS, A CORPORATION OF ILLINOIS.

BROOD-COOP.

1,199,205.

Specification of Letters Patent. Patented Sept. 26, 1916.

Application filed April 26, 1916. Serial No. 93,574.

To all whom it may concern:

Be it known that I, CHARLIE S. RIGGIN, a citizen of the United States, residing at Kankakee, in the county of Kankakee and 5 State of Illinois, have invented certain new and useful Improvements in Brood-Coops, of which the following is a specification.

My invention relates to sheet metal brooder coops and has especial reference to 10 brooder coops for poultry.

The object of my invention is generally to improve structures of this character and more specifically to provide a sturdy, rugged, inexpensive to manufacture and efficient 15 door for closure construction.

Other and further objects of my invention will become apparent, to persons skilled in the art, from a consideration of the following description when taken in conjunction 20 with the drawings, wherein:—

Figure 1 is an isometric perspective of the erected coop. Fig. 2 is a front elevation of the same. Fig. 3 is a side sectional elevation. Fig. 4 is a sectional elevation taken on line 25 4—4 of Fig. 3. Fig. 5 is a horizontal section. Fig. 6 is a section taken on line 6—6 of Fig. 8. Fig. 7 is an enlarged perspective view of the corner joint by which the vertical walls are held together. Fig. 8 is a section taken 30 on line 8—8 of Fig. 2. Fig. 9 is a view similar to that shown in Fig. 7, showing parts broken away, in section, to illustrate the manner of attaching the bottom wall to the vertical walls of the structure.

35 In all the views the same reference characters are employed to indicate similar parts.

The side walls 10 and 11 of the structure are, substantially, of the same size and configuration and each has a bottom edge 12 40 acutely upturned, into planes substantially parallel with the body part to strengthen the edge and to provide a means for holding the bottom wall 13 in place. Each vertical edge of the side walls is provided with outturned 45 rolls 14, which, in conjunction with a similar roll, made in the vertical edges of the rear and front walls, respectively, form the slip joints for the quadrilateral structure and serve to very materially strengthen the ver-

tical edges of the walls. The side walls 10 50 and 11 are tapered from the front edge to the rear edge, so that the top will shed water, the tapered edge of each side wall being out-turned to provide a flange at substantial right angles to the vertical portion, as at 15. 55 This out-turned flange provides a sliding member for the top 16. Close under the out-turned flange 15 of the side walls are a series of ventilating perforations 17. The top wall is provided on its overhanging side 60 with acutely inturned flanges or edges 18, to inclose the out-turned flanges 15 of the side members, and to provide sliding guides therewith when the top is placed over these members and slid into position. The rear 65 edge of the top member 16 is bent upon itself, as at 19, to provide a substantially smooth salient edge 20, and to strengthen this overhanging part of the structure, and is again bent, toward the edge 20, as at 21, 70 to provide a flange 21 to engage an inturned flange 22 of the rear wall 23, when the top is in place. The flange 22 serves to strengthen 75 the upper surface of the rear wall and to firmly hold the top and prevent it sliding 80 farther upon the upper surfaces of the underlying walls. The front surface of the top 85 16 is provided with a strengthening roll 24 which is downturned, the inner edge of which engages an out-turned flange 25 of 90 the front wall 26. The lower edges of the rear wall 23, and of the front wall 26, are upturned, as at 27 and 28, respectively, just as the side walls are upturned, to engage the four downturned flanges 29 of the bottom 95 13. The bottom 13 is rectangular in form and is designed to fit snugly in the four vertical walls being provided with four downturned flanges 29 for engagement with the upturned flanges from the lower edges of 90 said surrounding walls. This raises the bottom 13 above the lower surface of the structure and provides a dry, warm floor, which serves, in conjunction with the top, to hold the four vertical walls in rigid relative positions. The top 13 is provided, in diagonal corners, with rings 30 that are hinged thereto, as at 31. To remove the bottom it is only

necessary to lift the rings 30 and insert the fingers and raise the bottom from its position between the surrounding walls.

The back wall 23 is provided with vertically extending end rolls 32, somewhat larger than the rolls 14, and adapted to encompass the smaller rolls when the parts are assembled. When the top and bottom are removed from their association with the vertical side walls, the latter may be collapsed by bringing the diagonally opposite corners in substantially the same transverse plane. This will cause the back wall 23 to lie somewhat in a parallel relation with the side wall 11, and the side wall 10 will be in a substantially parallel plane with the front wall 26. When it is desirable to quickly compact the coop to place it in storage, after it has been in use, this is probably a quicker and better way to collapse it, to make it occupy smaller dimensions, than when the particular members are entirely separated. The rolls 14 and 32 are sufficiently large to permit considerable relative rotation, the one within the other, for the purpose specified. The vertical edges 14' and 32' of the respective rolls are turned at somewhat an acute angle, in substantially radial planes, and these angular parts are so disposed, with reference to each other when the side walls are in relative rectangular positions, as to permit the rotation of the member 14 within the member 32 to permit collapsing the side walls for the purpose specified. The back or rear wall 23 is provided with a series of ventilating openings 34 near the upper edge thereof which lie immediately under the projection 19 of the top 16 and like the openings 17 in the side walls of the structure, the overhanging wall or roof 16 prevents snow or water from being driven into the interior of the coop, owing to the close approximation of these ventilating perforations to the roof. The front wall 26 is provided with an entrance or door aperture 35, adapted to be covered by the sliding foraminous door 36, or the imperforate door 37. One boundary wall of the aperture 35 is out-turned, into a flange, as at 38, to provide a stop for the imperforate door 37. The door 37 is made of sheet metal and has each of its edges inturned into a flange, as at 39, to give strength to the door, the front flange 39 being in co-operative relation with the out-turned flange 38 of the wall 26 as a stop member, keeps the door 37 from sliding outwardly beyond the guides in which it is inclosed.

Secured to the front wall 26 of the structure is a forwardly projecting channel guide 40 having a part 41 riveted to the front wall, as by rivets 42, or by spot welding, as may be desired, and provided with a ledge portion 43 extending forwardly, and a down-

turned portion 44, spaced apart from the wall 26, a distance substantially equal to or a little more than the combined thickness of the doors 36 and 37. The ledge portion 43 is downturned, at the ends, as at 45, to provide stops to retain the doors within the channel so that they may not be moved too far in either direction. The channel 40 terminates in a forwardly projecting flange 46 carrying a suitable number of perforations 47. Projecting forwardly of the door 36 is a similar flange 48 provided with a perforation 49 for register with the perforation 50 in the flange 46, when the door is closed, so that a lock or other fastening device, may be passed through the said perforations to hold the door in closed position, as shown in Fig. 6. When the door 36 is open part of the way, so that the perforation 49 is in register with any of the perforations 47 in the flange 46, a nail or pin may be passed through the perforations 49 of the door and any one of the registering perforations 47 to hold the door in any selected position so that it may not be open farther unless the nail or other locking device be removed. When the door 36 is in closed position, the door 37 may be slid between the door 36 and the wall 26 to close the space left open by the meshes 51 in the wire cloth of the door 36.

Another channel 52, substantially as wide as the channel 40 above the doors, is provided at the lower extremity of the opening 35 and extends substantially across the front wall 26 of the coop. It is secured at each of its ends to the front wall, as by rivets 53 or the like, or by any other suitable means. The ends of the channel 52 are left open, so that any dirt that may accumulate therein will pass out through the openings in the ends, as the doors 36 and 37 are slidingly moved in the support.

Having described my invention, what I claim is:

1. In a coop the combination with one vertical wall thereof having an aperture therein to constitute a door-way, said aperture having an out-turned vertical edge; of an outwardly projecting door-guiding channel above the doorway and a similar channel below the door way extending practically across the wall, the lower channel open at its end; a foraminous door, and an imperforate door, slidably movable in said channels to close and open the door way, with either, said imperforate door having four inturned edges, one of which engages the out-turned edge of the door-way as a stop when the imperforate door is open.

2. In a coop the combination with one vertical wall thereof having an aperture therein to constitute a doorway, said aperture having an out turned vertical edge; of out-

wardly projecting door guiding channels above and below the doorway; a foraminous door, and an imperforate door slidably movable in said channels to close and open the doorway with either, one of said doors having a vertical inturned edge which engages the out-turned edge of the doorway as a stop when said door is open.

In testimony whereof I hereunto set my hand in the presence of two subscribing 10 witnesses.

CHARLIE S. RIGGIN.

In the presence of—

H. H. WHITTEMORE,
AURORA RUEL.
